MACHINE FOR TREATING HEELS

George H. Heys, Swampscott, Mass., assignor to
United Shoe Machinery Corporation, Paterson,
N. J., a corporation of New Jersey

Application April 20, 1931. Serial No. 531,375

11 Claims. (Cl. 12—42)

This invention relates to machines for treating heels and is herein illustrated in a so-called heel grading machine for cutting off a portion of a heel block in predetermined relation to the attaching 5 surface of the heel, this machine being of the type illustrated in United States Letters Patent No. 1,885,840, granted November 1, 1932, upon an application filed in the name of Ralph F. Knight.

In the production of wood heels, the tread 10 face of the heel, meaning the surface to which the top lift will be attached, is the last one to be formed. The angular relation between the tread face of the heel and the attaching face thereof and the vertical distance or height there- 15 between the important factors in determining the characteristics of the heel, and having once been determined, may not be disturbed without serious likelihood of spoiling the style of the heel and making it unsuitable for use in shoes of even 20 rather low grade. It becomes desirable, therefore, from the viewpoint of the heel manufacturer to facilitate detection of alterations of the heels in an attempt to make them fit a last for which they were not intended with the consequent like- 25 likelihood of producing an ill fitting heel which, if used, may seriously injure the reputation of the heel manufacturer.

To overcome this danger the present invention 30 makes provision for marking the freshly prepared tread surface of a heel subsequently to and as an incident of the heel grading operation. The invention is not limited, however, to embodiment in heel grading machines.

Heel grading machines are commonly provided 35 with an oscillating work carrier on which each heel is positioned and by means of which it is presented to a grading saw, the operator holding the heel on the carrier and releasing it therefrom so that it may fall into a suitable receptacle after 40 the grading operation. With this in view, one feature of the invention relates to a displaceable marking device arranged to be displaced so as not to interfere with the untreated heel when the latter is being presented to a grading saw and 45 positioned in the path of movement of and to mark the freshly prepared tread surface of the heel subsequent to the grading operation.

Still other features of the invention reside in 50 novel carrying mechanism for a marking device arranged yieldably to support the marking device in the path of movement of the tread face of a graded heel. As illustrated, this carrying mechanism includes a housing to protect the marking device from flying dirt, such as sawdust, and to 55 enclose an ink roll coacting with the marking de-

vice. As illustrated also, the carrying mechanism provides for adjustment of the level of the device and for adjustment to bring it into the plane of the saw and allows the whole marking device to be readily moved into inoperative position when 60 desired and as easily returned to its operative position.

In the accompanying drawings,

Fig. 1 is a plan view of a grading machine and 65 its marking device;

Fig. 2 is a perspective view of a heel looking 70 at the tread surface thereof and showing a marking thereon;

Fig. 3 is an enlarged plan view of the marking 75 device; and

Fig. 4 is a front elevation thereof together with 80 its supports.

The heel grading machine, a complete description 85 of which will be found in the Knight application, to which reference has been made above, 75 comprises a frame 10 in which there is journaled a rotary grading saw 12 and on which are mounted supporting brackets 14 for a shaft 16 secured to which is a swinging heel carrier 18. This carrier 80 has an adjustably positioned plate 20 against 85 which the attaching surface of the heel is rested and a breast surface engaging arm 22 and is provided with a weight 24 to return it, when released, to a vertical position at right angles to that illustrated in Fig. 1. The operator will position a heel 90 against the plate 20 and the arm 22 and, holding it there with his fingers, will swing the carrier to move the heel in an arc intersecting the circumference of the saw 12 so that a portion 26 of the heel, which may have a dowel pin 28 projecting 95 therefrom, will be removed and a tread surface 30 produced upon the heel in exactly the desired angular relation to the attaching surface 90 thereof. The height of the heel may be adjustably determined by laterally displacing the shaft 95 16 by means of a hand wheel 32 as described in said application.

Referring now more particularly to Figs. 3 and 100 4, it will be seen that the marking device or wheel 34, embodying a peripheral band of rubber with 105 type faces thereon, is freely rotatable in a recess 36 within a carrier 38 which is secured by a set screw 40 (Fig. 3) to the upper end of a stud 42 (Fig. 4). This stud passes substantially vertically through an angle piece 44 pivoted at 46 upon an arm 48 adjustably secured to a bracket 50. This bracket 50 is bolted to the frame 10 of the 110 grading machine and provision is made for a vertical adjustment of the arm 48 by means of a clamping bolt 52 passing through a slot 54 in the

bracket 50 to bring it into the path of heels mounted in the swinging carrier 18.

The marking device is arranged to be normally held in the position illustrated in Fig. 3 by means of a coiled spring 56 surrounding the stud 42 and having one end attached to the angle piece 44 and the other end to a nut 58 secured to the lower end of the stud 42. This permits displacement of the heel carrier 38 of the marking device when it is engaged by the dowel pin 28 or by a projecting corner of the portion 26 of a heel mounted in the carrier 18 and being presented to the grading saw 12, said marking device when displaced occupying the position indicated in dotted lines in Fig. 1. 10
15 As soon as the heel is carried in its swinging movement toward the saw past the marking device the latter will swing back to a position where the marking wheel 34 lies in the path of movement of the treated surface 30 upon the heel 25 as the carrier 18 is allowed to swing back to vertical position. As a result the inked type upon the marking wheel will move across the surface 30 and produce a mark 60 thereon, which mark, of course, 20
25 may be varied and arranged to satisfy the needs of any particular heel manufacturer.

Associated with the marking wheel within the recess of the carrier 38 is a pivotally mounted ink roll 62 of felt or the like which is saturated with ink and which rolls over the surface of the marking wheel 34 as the latter is turned by its engagement with the heel. The position of the marking wheel 34 when engaged by the heel is resiliently determined by means of a spring member 64 having an inturned end 66 and secured to the angle piece 44 by means of a screw 68 and a pin 70. The spring 56 serves to return the marking wheel 34 and its carrier 38 into the position determined by said spring 64 and the spring 64 provides enough yield so that there is no danger of 30
35
40
45 injury to the marking device as a result of engagement by the heel 25.

Protection of the marking device and ink roll from falling dirt such as sawdust is afforded by a cover 72 at the rear side of the carrier 38 and a cover 74 at the front side thereof. At its upper edge, the cover 74 has a folded-over portion 76 overlying the top surface of the carrier 38. This overlapping portion 76 is slotted at 78 for engagement with a clamping screw 80 and the left-hand 50 end of the cover 74 is curled around a pin 82.

A finger screw 84 extending between the angle piece 44 and the arm 48 provides for adjustment of the angular relation between the marking surface of the wheel 34 and the plane of one side of the saw 12, thus enabling the marking device to be brought into correct marking relation to the freshly prepared tread surface of a heel mounted in the swinging carrier 18. In order that the marking device may be moved readily to an inoperative position when it is not desired for use and as readily returned to its predetermined operating position, the screw 84 passes through a slot in the upper end 86 of the bracket 48 and is held frictionally in this slot by means of a spring 88 surrounding the screw and pressing against a convex washer 90 engaging the side of the slotted end 86 of the bracket 48. When it is desired to displace the marking device by swinging the block 44 around the pivot 46, this may be done 60
65
70
75 simply by grasping the screw 84 and pulling it out of the slot in the upper end 86. When the marking device is returned to marking position, the convex faces of the washer 90 and of the lower side of the head of the screw 84 facilitate the re-engagement of said screw in the slotted end 86.

When it becomes necessary to apply ink to the inking roll 62, access thereto can readily be obtained by loosening the screw 80 and sliding the cover plate 74 to the left so as to disengage it from the pin 82, after which the cover plate can be either completely removed or swung around the screw 80. If it becomes desirable, the abutment spring 64 can be dropped out of position by springing it off the pin 70 and turning it in a counterclockwise direction on the screw 68. 80
85

It will be understood that marking tools of other sorts may be substituted for the rubber-faced type wheel 34 illustrated herein. It may be desired not to apply an inked mark but rather to make an indentation in the form of lines, dots, etc., by means of a knurling tool, for example, which will escape notice by persons other than the heel manufacturer. Further protection against duplication of the mark may be secured by utilizing peculiar or imperfect type. When an inked mark is employed, the color of the ink used may indicate the month or season when the heel was graded. 90
95

The operation of the device will be apparent from the previous description and it will be seen that it is entirely automatic, requiring no thought from the operator of the grading machine and needing attention only at rare intervals when the supply of ink is exhausted. 100

Having thus described my invention, what I claim as new and desire to secure by Letters Patent of the United States is: 105

1. In combination, means for operating upon an article to provide a fresh surface on the article comprising an operating tool and a swinging support for the article, and a marking device for marking the freshly prepared surface, said marking device being constructed and arranged for displacement as an article is carried to said operating tool and for return to marking position for engagement with the freshly prepared surface upon the return movement of the support. 110
115

2. In combination, means for operating upon a heel to trim away a portion of the material and provide a fresh surface thereon comprising an operating tool and a heel support, and a marking device arranged for engagement with the freshly prepared surface of the heel, said marking device being constructed and arranged for displacement by the heel as the heel is moved toward the tool. 120
125

3. In combination, grading means, means for operating upon a heel to trim away a portion of the material and provide a fresh surface thereon comprising an operating tool, a movable heel support constructed and arranged to support a heel in predetermined relation to said tool, and marking means operating in time relation to the grading means to apply a mark to the fresh surface on the heel while carried by said movable support. 130
135

4. In combination, grading means for operating upon a heel to trim away a portion of the material and provide a fresh surface thereon comprising an operating tool and an oscillatory heel support constructed and arranged to support a heel in predetermined relation to said grading means, and a marking device arranged for engagement with the freshly prepared surface of the heel during the recessional movement of the oscillatory heel support. 140
145

5. In a marking device, an oscillating heel support, a marking member, a swinging carrier for the marking member, and means for automatically swinging said carrier to bring the mark- 150

- ing member into position for marking engagement with a heel on the support.
6. In combination, a frame, a grading saw, a swinging heel support pivoted on said frame, a housing pivotally mounted on said frame, a marking device carried by said housing, resilient means tending to turn said housing to carry the marking device into position for engagement with the tread face of the graded heel, and a resilient stop engaging the housing in opposition to said turning means, said stop being constructed and arranged to support the housing and the marking device against the pressure of a heel passing the marking device.
- 15 7. In a marking device for a heel grading machine having a frame, a grading saw, and a swinging heel carrier mounted on said frame, a bracket pivotally secured to said grading machine, a marking device swingingly carried on said bracket, and releasable means for holding said bracket normally in position to support the marking device in the path of the work constructed and arranged for release to allow the marking device to be moved to an inoperative position outside the path of the work.
- 20 8. In a marking device for a heel grading machine, an oscillating support for a work piece, a swingingly mounted carrier, a marking wheel pivoted in said carrier, an ink roll pivoted in said carrier for engagement with said marking wheel, and a dirt-excluding housing surrounding said ink roll and a portion of said marking wheel with the latter projecting beyond the housing for engagement with the work, said housing and said carrier being arranged to be displaced to an inoperative position upon movement of the work support in one direction and arranged to be returned automatically to operative position.
- 25 9. In combination, a frame, a heel grading saw on said frame, a heel carrier swingingly mounted
- on the frame to carry a heel in an arc intersecting the circumference of the saw, a rotary marking device pivotally mounted on said frame for displacement by engagement with an ungraded heel as the carrier is swung toward the saw, and means for automatically returning said marking device to a position where it will roll over the tread face of a graded heel as the carrier is returned to work receiving position.
10. In combination, a grading saw, a swingingly mounted heel carrier normally positioned in front of the saw to receive a heel and capable of swinging movement to carry the heel toward the center of the saw together with means for returning said carrier to work receiving position, a marking device comprising a printing wheel journaled in a pivotally mounted housing positioned in the path of inward movement of the heel and adapted to be displaced by the projecting end of the heel as it is carried toward the saw, a spring for turning said housing to bring the marking wheel into the path of the tread face of the heel, and means for resiliently supporting said housing to permit a firm but resilient engagement of the marking wheel with the tread face of the freshly graded heel.
- 15 11. In combination, an operating tool, a movable support for a work piece to be treated by said tool, a carrier, a marking device pivoted in said carrier, an ink roll pivoted in said carrier for engagement with said marking device, and a protective housing surrounding said ink roll and a portion of said marking device, said housing being positioned and adapted to be engaged by the work piece when the support is moved in one direction to move said marking device from a normally operative position to an inoperative position outside of the path of movement of the work.
